SPERMICIDES

Nathaniel M. Elias, New York, N. Y.

No Drawing. Application February 2, 1944,
Serial No. 520,774

6 Claims. (Cl. 167—58)

1

This invention relates to compositions useful for topical remedies which will be used chiefly in contact with the mucous membranes in the vaginal cavity. The topical remedies of this invention comprise spermicidal compositions which may range in pH value from 1.0 to 7.0, that is, from fairly acid to neutral compositions. One advantage of this invention is the fact that such a range of pH values is possible, since I have found a class of spermicidal substances suitable for such compositions which are neutral and relatively harmless. In this way, the spermicidal activity and the acidity are separated one from the other and a pH may be chosen which is best suited for the physiological environment, the pH being established by means of whatever simple organic or inorganic acids and buffer salts may seem desirable. The limitations of pH 1.0 to pH 7.0 are given because it has been found that there is a tendency for the tissues to be irritated by a pH lower than 1.0 or higher than 7.0. Also pH of 7.0 is given as an upper limitation because above this pH an environment is created which may make undesirable infections possible. The invention will now be more particularly described.

I have discovered that a large class of neutral aliphatic hydroxy compounds are definitely spermicidal when sufficiently subdivided, and are not at all or negligibly irritating, so that highly spermicidal compositions can be made with them for topical use. The smaller the subdivision in a suitable vehicle the more effectively spermicidal the compound. In the case of insoluble substances of this class, the emulsion particles should be under 1.5 microns down to actual solution in the case of the soluble compounds, where the particles may be considered to be molecular in size. This class includes the following:

(a) Straight chain fatty monohydroxy alcohols having from 8 to 11 carbon atoms in the chain,

(b) Branched chain fatty alcohols from 8 to 18 carbon atoms in the chain,

(c) Glycerol or ethylene glycol or propylene-glycol monoethers of the alcohols mentioned in (a) and (b),

(d) Polyethylene glycol or polypropylene glycol mono ethers of these alcohols, the poly glycols ranging from the diglycol up to polyglycols of molecular weight of about 4000,

(e) Glycerol or ethylene glycol or propylene

2

glycol monoesters of unsaturated fatty acids having from 10 to 18 carbons in the chain,

(f) The polyethylene glycol and the polypropylene-glycol mono esters of fatty acids, saturated and unsaturated, having from 10 to 18 carbons in the chain, the poly glycols ranging in molecular weight from diglycol to poly glycol of molecular weight of about 4000,

(g) Glycerol monolactate monoesters of unsaturated fatty acids of 10 to 18 carbon atoms.

It will be noted that these compounds comprise higher fatty alcohols, hydroxyethers, hydroxy esters and hydroxy ester ethers. Examples of the fatty alcohols are n-ethyl hexanol (branched chain), n-octanol (straight chain), n-decanol (straight chain), undecanol (branched chain), tetra decanol (branched chain) and heptadecanol (branched chain). These fatty alcohols have the formula ROH where R is the fatty chain.

20 Examples of the hydroxy ethers are the glycerol, the propylene glycol-, the diglycol-, the ethylene glycol-, the nonaethylene glycol, the duodecaethylene glycol, -the polyethylene glycol (molecular weight 1500)-mono ethers of the above alcohols.

The hydroxy ethers of the fatty monohydric alcohols may be made by etherifying one molecule of a poly hydroxy alcohol with one molecule of the fatty monohydroxy alcohol according to the following equation:

where ROH is the fatty alcohol, $R_1(OH)_n$ is the polyhydroxy alcohol or poly glycol, and n is any integer equal to or greater than two.

35 The fatty hydroxy esters which are effective for spermicidal use include compounds in which the fatty chain ranges from about ten to eighteen carbon atoms. They may be saturated or they may be unsaturated with one or more than one double bond. They may be hydroxylated; that is, they may carry an hydroxyl group substituted in the fatty chain.

The polyhydric alcohols with which the fatty acids are esterified include ethylene- and propylene-glycol, glycerine and poly alcohols higher than glycerine. For commercial purposes sorbitol and mannitol, which are the highest polyhydric alcohols now available, would constitute the practicable upper limit. They also include the vari-

ous ether and poly ether polyhydric alcohols, such as the poly-ethylene- and polypropylene- glycols. The poly ethylene glycols have the following formula:

where n may be any integer from 1 to about 90.

Polypropylene glycols have a similar structure except that there is a methyl group added for every two carbons in the chain.

The mono ethers of the glycols and the poly glycols may also be formed by reacting ethylene oxide or propylene oxide with the monohydroxy alcohol itself as follows:

$(n+1)\text{C}_2\text{H}_4\text{O} + \text{ROH} \rightarrow \text{ROCH}_2(\text{CH}_2\text{OCH}_2)_n\text{CH}_2\text{OH}$

Here $\text{C}_2\text{H}_4\text{O}$ is ethylene oxide, ROH is the fatty alcohol, and n may be zero, in which case the group $(\text{CH}_2\text{OCH}_2)$ disappears, or may be any integer above zero.

The mono esters of the glycols and poly glycols may be formed similarly as follows:

By taking a mono glyceride of a fatty acid and esterifying it further with one molecule of lactic acid and by the elimination of one molecule of water by means of heat alone or by the use of a catalyst, there is obtained a monolactate of the monofatty ester of glycerine. This has one residual hydroxyl group left free on the glycerine molecule and has an additional hydroxyl group left on the lactate portion of the molecule. Such compounds come within the scope of this invention. This class of compound has the following general formula:

where R is the hydrocarbon residue of the higher fatty acid.

In general, I have found that a greater number of hydroxyl or ether radicals in the hydrophilic group are necessary to produce spermicidal products in compounds where the fatty portion of the molecule is saturated than where the fatty portion of the molecule is unsaturated or hydroxylated. In such saturated compounds I have found that the longer the molecular chain of the fatty portion the greater the number of hydroxyl radicals or hydroxyl and ether radicals needed in the hydrophilic group to produce a spermicidal compound.

In using any of the compounds for spermicidal work it is necessary to have them thoroughly emulsified and suitable emulsifying agents are generally desirable. This emulsification is essential since if the particles are small the spermicidal value is improved. When the compounds become water soluble as in the case of the higher polyglycol esters and ethers, the presence of an emulsifier is not essential. However, here also it may be desirable to assist in the wetting action of the product in use.

Examples of the esters of the higher saturated fatty acids suitable for this invention are the following:

The mono stearates, the monohydroxy stearates, the monopalmitates, the mono myristates, the mono laurates and monocaprates of nona ethylene glycol, hexaethylene glycol, diethylene glycol, polyethylene glycol (molecular weight

1500), poly propylene glycol (molecular weight 1000), duo decaethylene glycol, etc.

In the case of esters containing unsaturated higher fatty radicals the same comments apply as in the case of the saturated compounds. These compounds have much lower melting points than the esters made with saturated fatty radicals, and so emulsify more readily. The glyceryl mono esters of the various eighteen carbon unsaturated fatty acids are quite effective, as are the ethylene and propylene glycol mono esters.

Similarly, the polyethylene and polypropylene glycol esters show strong spermicidal values. In this case also, the effectiveness of the products are enhanced by the use of emulsifying agents which reduce the surface tension and by thorough emulsification, especially with those compounds which are insoluble in water and not self-dispersible. Here also it is desirable to use them in neutral or acid solution.

Examples of the unsaturated compounds which are found to be spermicidal are the following:

The mono-oleates, -ricinoleates, -linoleates, -linolenates, ricinolenates and undecylenates of the following poly hydroxy compounds: Glycerine, ethylene glycol, propylene glycol, diethylene glycol, tripropylene glycol, tetraethylene glycol, hexaethylene glycol, nonaethylene glycol, duodecaethylene glycol, polyethylene glycol (molecular weight 1500), polypropylene glycol (molecular weight 1000), polyethylene glycol (molecular weight 4000), sorbitol, mannitol, sorbitan and glyceryl monolactate.

In any of the formulae herein given, where water soluble fatty hydroxy esters or fatty hydroxy ethers are used, there is an approximate molecular equivalence in spermicidal power so that substitutions of one for another of the esters or ethers may be made in proportion to their molecular weights.

There appears to be a slight advantage in the water soluble compounds in favor of the unsaturated esters and ethers as compared to the saturated esters, but as a rough guide molecular equivalence is helpful. Accordingly,

in Formula 1 below, 3 lbs. of nona ethylene glycol monolaurate has been used. If now polyethylene glycol laurate is used having a molecular weight of 1682 (made from polyethylene glycol of molecular weight 1500), then, since the molecular

weight of nona ethylene glycol monolaurate is 596, it would be necessary to use 2.82 times as much or 8.46 lbs. to obtain a roughly equivalent spermicidal jelly. If a poly glycol stearate of molecular weight 1086 (made from a polyethylene glycol of molecular weight 820) be used, 1.8 times as much or 5.4 lbs. would be desirable. If a nona ethylene glycol undecylenate were used, having a molecular weight of 578, somewhat less than 2.9 lbs. would be approximately equivalent.

Molecular equivalence while applying fairly well to the water soluble compounds applies to a much smaller degree only to the water insoluble compounds. Here the degree of dispersion is an important factor. However, in general, the greater the dispersion and the more finely divided the particles the more spermicidal is the finished composition.

Having thus described the range of spermicidal substances coming within the scope of the present invention, I shall now give examples of how they may be used in finished spermicidal compositions. In accordance with the present invention, the said substances are uniformly distributed in vehicles to form various spermicidal compositions, 75 these compositions being generally classified as

jellies, creams, concentrated foam jellies, concentrated foam producing mixtures, concentrated foam powders, suppositories and tampons. The particle size of the said substances in said vehicles varies from molecular, i. e., a solution, to approximately 1.5 microns.

JELLIES

In general it should be noted that in any of the following jelly formulae glycerine is added to prevent dehydration of the jelly and also to prevent freezing of the composition. The various vegetable gums, such as gum tragacanth, gum karaya and gum arabic may be substituted by other gums such as Irish moss, Indian gum, alginates, synthetic cellulose derivatives such as colloresin, locust bean gum, etc. The butyl para hydroxy benzoate may be substituted by other mold preventive material such as the methyl, ethyl or propyl para hydroxy benzoates. The oxyquinoline sulphate may be substituted by other bacteriostatic materials such as the phenols, the alkali alkyl sulphates, etc. The emulsifying agent, sodium lauryl sulphate may be substituted by any of the known alkali, ammonium or substituted ammonium alkyl sulphates or other sulfonated substances such as sulfonated oils, sulfonated hydrocarbons, sulfonated castor oil and similar products.

The water soluble acids which may be substituted for lactic or boric acids as shown in the formulae may include acetic acid, tartaric acid and similar acids. The potassium acetate as shown in the formula is a buffer and may be substituted by sodium acetate or by alkali borates, tartrates, phosphates, lactates, etc.

It is understood that where the water soluble organic acids are used they exert a certain known spermicidal power, but this spermicidal power alone is insufficient to achieve the effectiveness now possible with these new compositions.

In the case of boric acid, this product has very slight spermicidal efficacy and is used simply for regulating the pH of the composition. The fact that compositions of extremely high spermicidal value, even though neutral, are made possible by this invention, establishes the utility of these compositions regardless of the presence or absence of added acid.

The proportion of the gums used indicates the viscosity range chiefly preferred, but such viscosities may range either lower or higher than indicated in the compositions described without seriously affecting the utility of the product.

NEUTRAL JELLIES USING WATER SOLUBLE MONO FATTY ESTERS WITH NO EMULSIFIER

Formula 1

	Pounds
Nona ethylene glycol mono laurate	3.0
Oxyquinoline sulphate	0.05
Glycerine	10.0
Gum tragacanth	2.0
Gum karaya	1.0
Gum arabic	0.5
Butyl para hydroxy benzoate	0.05
Perfume	0.05

Bring to pH of 7.0 with trace of NaOH.

Add sufficient water to make total of ---- 100

ACID JELLIES USING WATER SOLUBLE MONO FATTY ESTERS AND A WATER SOLUBLE ORGANIC ACID AND NO EMULSIFIER

Formula 2

	Pounds
Nona ethylene glycol mono laurate	3.0
Oxyquinoline sulphate	0.05
Glycerine	10.0
Lactic acid—85%	2.35
Gum tragacanth	2.0
Gum arabic	0.5
Gum karaya	1.0
Butyl para hydroxy benzoate	0.05
Potassium acetate, sufficient for pH of 3.0	About 0.05
Perfume	0.05

Add sufficient water to make ---- 100.00

In this type of formula, using water soluble esters, the approximate equivalence rule given previously applies.

Less of the spermicidal ester is used here than in Formula 1, since part of the spermicidal action is provided by the lactic acid.

However, more of the ester may be used if a still more spermicidal composition is desired.

ACID JELLIES USING WATER SOLUBLE MONO ESTERS AND BORIC ACID

Formula 3

	Pounds
Nonaethylene glycol mono laurate	2.0
Sodium lauryl sulfate	0.5
Gum tragacanth	3.0
Glycerine	10.0
Gum arabic	0.5
Butyl para hydroxy benzoate	0.05
Boric acid—adjust pH to 4.3	About 0.5
Perfume	0.05

Water sufficient to make a total of ---- 100.00

Here boric acid is used, and since this contributes little to the spermicidal value, 3 lbs. of the ester are used. In addition, sodium lauryl sulphate is used which has a bacteriostatic action as well as a wetting action so the oxyquinoline sulphate may be omitted. The function of the boric acid is simply to bring the composition to a pH value of 4.3.

NEUTRAL JELLIES USING WATER INSOLUBLE MONO FATTY ESTERS WITH ADDED EMULSIFIER

Formula 4

	Pounds
Glyceryl mono undecylenate	3.0
Sodium lauryl sulfate	0.5
Glycerine	10.0
Gum tragacanth	3.0
Gum arabic	0.5
Butyl para hydroxy benzoate	0.05
Perfume	0.05

Bring to pH of 7.0 with trace of NaOH if necessary.

Add sufficient water to make total of ---- 100.00

The sodium lauryl sulfate here assists in the dispersal of the glyceryl mono-undecylenate as well as exerting a bacteriostatic action.

ACID JELLIES USING WATER INSOLUBLE MONO FATTY ESTERS AND AN ACID

Formula 5

This formula is identical with Formula 3 except that the 2 lbs. of nonaethylene glycol lau-

rate is replaced by 2 lbs. of glyceryl monoricinol-
eate.

**ACID JELLIES USING WATER INSOLUBLE HIGHER
FATTY ALCOHOLS WITH ADDED EMULSIFIER**

Formula 6

	Pounds
n-Decyl Alcohol	1.0
Sodium lauryl sulfate	0.8
Glycerine	10.0
Gum tragacanth	3.2
Gum arabic	0.7
Butyl para hydroxy benzoate	0.05
Perfume	0.05
Boric acid—adjust pH to 4.3	About 0.5

Water sufficient to make total 100.0

**ACID JELLIES USING WATER INSOLUBLE MONO FATTY
ETHER AND BORIC ACID**

Formula 7

This formula is identical with Formula 3 except that 2 lbs. of the glyceryl mono ether of octyl alcohol are used instead of 3 lbs. of nona-ethylene glycol monolaurate.

**JELLIES IN WHICH BOTH A WATER SOLUBLE AND
WATER INSOLUBLE ESTER ARE USED**

Formula 8

	Pounds
Nona ethylene glycol mono laurate	1.5
Glyceryl mono ricinoleate	1.5
Glycerine	10.0
Oxyquinoline sulfate	0.05
Gum Tragacanth	3.0
Gum arabic	0.5
Boric acid to adjust pH to 4.3	About 0.5
Perfume	0.05

Water sufficient to make a total of 100.0

Here the nonaethylene glycol monolaurate assists in emulsifying the glyceryl monoricinoleate and they both exert spermicidal action, which is additive.

**JELLIES IN WHICH A WATER SOLUBLE MONO FATTY
ETHER IS USED**

Formula 8A

2.5 lbs. nona ethylene glycol mono ether of octanol is substituted for the 3 lbs. of nona ethylene glycol laurate in Formula 2.

CREAMS

In forming spermicidal creams, I have found it essential to provide a suitable cream base to carry the spermicidal material. Such a base is made up of a high molecular alcohol such as stearyl alcohol or cetyl alcohol or saturated mono-higher fatty esters of glycerine or sorbitan or glyceryl mono lactate with an emulsifier such as one of the alkyl sulfates and water. I have found it convenient to reduce the cost of such a base by diluting it with stearic acid in which case the more costly high molecular alcohols such as cetyl and stearyl or the saturated mono fatty esters of glycerine or of sorbitan or of glyceryl monolactate are required in less quantity.

Because of the necessity for emulsifying the base forming constituents of the creams, it is essential always to have in the composition an emulsifying agent. It must be present in amount sufficient to emulsify the base, and in case a water insoluble non-self-dispersible spermicidal material is used, there must be sufficient in addition for emulsifying this also. Of course, where the spermicidal agent is self emulsifying some-

what less of the emulsifier will be required than is otherwise the case. This is also true where the spermicidal agent is water soluble.

**NEUTRAL CREAM USING WATER SOLUBLE AND WATER
INSOLUBLE MONO FATTY ESTERS**

Formula 9

	Pounds
Glyceryl mono stearate	18.0
Glyceryl mono laurate	2.0
Glycerine	8.5
Nona ethylene glycol undecylenate	2.0
Sodium lauryl sulfate	0.7
Perfume	0.05

15 Adjust to pH of 7.0 with either boric acid or NaOH.

Water sufficient to total 100.0

**ACID CREAM USING WATER SOLUBLE AND WATER
INSOLUBLE MONO FATTY ESTERS**

Formula 10

	Pounds
Glyceryl mono stearate	5.5
Stearic acid	10.0
Sorbitan stearate	4.5
Nona ethylene glycol mono laurate	3.0
Glycerine	8.5
Sodium lauryl sulfate	0.6
Lactic acid 85%	1.2
Potassium acetate to adjust pH to 3.3	About 0.2

Water sufficient to make total 100.0

**ACID CREAM USING MIXTURE OF WATER INSOLUBLE
MONO FATTY ESTERS**

Formula 11

	Pounds
Stearic acid	18.0
Sorbitan stearate	4.5
Glyceryl monoricinoleate	2.0
Glycerine	8.5
Sodium lauryl sulfate	0.6
Boric acid—adjust to pH of 4.3	.05

Water sufficient to make total 100.0

**ACID CREAM USING ONLY WATER SOLUBLE MONO
FATTY ESTERS**

Formula 12

	Pounds
Stearic acid	4.0
Stearyl alcohol	8.0
Nona ethylene glycol mono laurate	3.0
Glycerine	8.5
Sodium lauryl sulfate	0.5
Lactic acid 85%	2.0
Potassium acetate to adjust pH to 3.0	About 0.3
Perfume	.05

Water sufficient to make total 100.0

**OTHER CREAM FORMULAE SHOWING VARIATIONS IN
THE INGREDIENTS FOR THE BASE**

Formula 13

	Pounds
Stearic acid	19.0
Glycol monoricinoleate	1.3
Sodium lauryl sulfate	0.8
Stearyl alcohol	1.0
Potassium acetate	0.2
Lactic acid 85%	1.2
Glycerine	8.0

75 Water sufficient to make total of 100.0

9
Formula 14

	Pounds
Glyceryl monostearate	18.0
Nonaethylene glycol laurate	3.0
Sodium lauryl sulfate	0.9
Boric acid	2.0
Glycerine	8.0

Water sufficient to make total of 100.0

Formula 15

	Pounds
Glyceryl monostearate	10.0
Stearic acid	10.0
Nonaethylene glycol laurate	2.0
Sodium lauryl sulfate	0.7
Boric acid	2.0
Glycerine	8.0

Water sufficient to make total of 100.0

Formula 16

	Pounds
Stearic acid	18.0
Glyceryl monostearate	2.0
Sodium lauryl sulfate	0.8
Glyceryl monoricinoleate	1.3
Boric acid	1.0
Glycerine	8.0

Water sufficient to make total of 100.0

CONCENTRATED FOAM JELLIES

For concentrated foam producing jellies, powders or similar mixtures to be used with moist sponges or moist tampons, it is desirable to have very high concentrations of spermicidal materials, since a small amount only is used on the sponge or tampon. The sodium alkyl sulfate assists the polyglycol mono ester in foam formation.

The following formulae are examples of my new compositions for this purpose.

CONCENTRATED FOAM JELLIES FOR USE WITH MOIST SPONGE OR TAMпон USING WATER SOLUBLE MONO FATTY ESTER**Formula 17**

	Pounds
Nonaethylene glycol laurate	20.0
Sodium lauryl sulfate	5.0
Gum tragacanth	3.0
Boric acid	2.0
Perfume	0.1
Glycerine	8.5

Water sufficient to make total of 100.0

Formula 18

This is identical with Formula 17 except that the nonaethylene glycol laurate is replaced with 20 lbs. of glyceryl monoricinoleate, which is insoluble.

CONCENTRATED FOAM PRODUCING MIXTURE WHICH MAY BE USED WITH MOIST TAMpon OR MOIST SPONGE USING WATER SOLUBLE MONO FATTY ESTER**Formula 19**

	Pounds
Nonaethylene glycol laurate	20.0
Boric acid	4.0
Gum arabic	2.0
Sodium lauryl sulfate	5.0
Perfume	0.1
Glycerine	10.0

Water to make total of 100.0

10
FOAM POWDERS

The vehicle in the case of the foam powders consists of kaolin and sucrose and lauryl sulfate. The spermicidal material is uniformly mixed throughout the powder.

CONCENTRATED FOAM POWDER FOR USE WITH MOIST SPONGE OR TAMpon

	Pounds
10 Kaolin	50
Sucrose	30
Sodium lauryl sulfate	5
Glyceryl monoricinoleate	15
15 Perfume	0.1

Formula 21

Same as previous formula except that 15 lbs. of 20 nonaethylene glycol mono laurate is substituted for the 15 lbs. of glyceryl monoricinoleate.

SUPPOSITORIES

For suppositories, two types may be used. The 25 first is that which melts at body temperature. Here the vehicle used is the higher molecular weight polyglycols themselves — in which the spermicidal factor is uniformly mixed. Examples are as follows:

	Pounds
30	
To 96 parts polyethylene glycol of molecular weight 1500 is added 4 parts of nonaethylene glycol mono undecylenate and both are melted 35 together.	
This mixture is then adjusted to a melting point of 36.5 by the addition of poly ethylene glycol of molecular weight 4000.	
The resulting product is melted and cast in suppository molds.	

Formula 22

To 96 parts polyethylene glycol of molecular weight 1500 is added 4 parts of the laurate ester 45 of poly ethylene glycol (molecular weight 400) and 2 lbs. of boric acid, and further adjustments of melting point are made by the addition of the poly glycols of molecular weight 4000, to obtain a melting point of 36.5° C. The ingredients are melted together and then cast in suppository molds.

This mixture is then adjusted to a melting point of 36.5 by the addition of poly ethylene glycol of molecular weight 4000.

The resulting product is melted and cast in suppository molds.

Formula 23

To 96 parts of poly ethylene glycol of molecular weight 1500 is added 4 parts of the laurate ester 45 of poly ethylene glycol (molecular weight 400) and 2 lbs. of boric acid, and further adjustments of melting point are made by the addition of the poly glycols of molecular weight 4000, to obtain a melting point of 36.5° C. The ingredients are melted together and then cast in suppository molds.

For suppositories stable at higher temperatures, the following formulae may be used. These depend on solubility of the vehicle or the spermicidal 55 ingredient or both.

Formula 24

To 96 lbs. of a poly ethylene glycol of melting point of 50° C. is added 2 lbs. of boric acid and 4 60 lbs. of a poly ethylene glycol mono laurate having a molecular weight of 800. The mixture is melted together and then cast in suppository molds.

65 SPERMICIDAL TAMPONS TO BE USED WITH ADDED MOISTURE

Here cotton, lambs wool, or other fibre and the added water constitutes the vehicle through which the spermicidal factor is distributed.

Formula 25

Cotton, lambs wool, natural or artificial silk or nylon fluff are impregnated with a water solution containing 50 parts of nonaethylene glycol mono laurate and 3 parts boric acid in a total of 100.

The material is pressed until there remains in it only 10% of the solution. It is then cut up into tampons weighing approximately 5 grams each, provided with strings, packaged and sterilized.

Formula 26

Identical with formula 25 except that the monoethylene glycol laurate solution is replaced by molten polyethylene glycol mono laurate of molecular weight of about 1700.

Formula 27

Identical with formula 25 except that the monoethylene glycol laurate solution is replaced by molten polyethylene glycol mono undecylenate of molecular weight of about 1680.

I have described what I believe to be the best embodiments of my invention. I do not wish, however, to be confined to the embodiments set forth, but what I desire to cover by Letters Patent is set forth in the appended claims.

I claim:

1. A harmless spermicide comprising a non-alkaline vehicle and a neutral aliphatic hydroxy material of sufficient spermicidal power and in sufficient proportions to constitute the major spermicidal ingredient in total spermicidal effect distributed therein, the size of the particles of the material distributed ranging from molecular to approximately 1.5 microns, said material being selected from the class consisting of (a) straight chain fatty monohydroxy alcohols having from 8 to 11 carbon atoms in the chain, (b) branched chain fatty alcohols from 8 to 18 carbon atoms in the chain, (c) glyceryl, ethylene glycol and propylene-glycol monoethers of the alcohols mentioned in (a) and (b), (d) polyethylene glycol and polypropylene glycol mono ethers of these alcohols, the poly glycols ranging from the diglycol up to polyglycols of molecular weight of about 4000, (e) glyceryl, ethylene glycol and propylene glycol monoesters of unsaturated fatty acids having from 10 to 18 carbons in the chain, (f) the polyethylene glycol and the polypropylene-glycol monoesters of fatty acids, saturated and unsaturated, having from 10 to 18 carbons in the chain, the polyglycols ranging in molecular weight from diglycol to polyglycol of molecular weight of about 4000, (g) glyceryl monolactate monoesters of unsaturated fatty acids of 10 to 18 carbon atoms, and mixtures thereof, the consistency of the vehicle being such that when the material is

distributed throughout it, the resulting composition may be positioned for effective action in a body cavity.

2. The spermicide as defined in claim 1, in which the vehicle is an aqueous vehicle.

3. The spermicide as defined in claim 1 and containing a water soluble acid for bringing the pH of the resulting composition within the range of 7.0 to approximately 1.0.

4. The spermicide of claim 1 in which the vehicle consists of water and an aliphatic compound in emulsified form, selected from the group consisting of glyceryl-, anhydrohexitoether and glyceryl monolactate-monoesters of the saturated fatty acids ranging from 10 to 18 carbon atoms in the fatty chain, cetyl alcohol, stearyl alcohol and stearic acid.

5. The spermicide as defined in claim 1 and containing a substance for reducing the surface tension of the composition.

6. The spermicide as defined in claim 1 and containing a buffer.

NATHANIEL M. ELIAS.
